UNITED STATES PATENT OFFICE.

JAMES LOGAN FITTS, OF MERCHANTVILLE, NEW JERSEY, ASSIGNOR TO WARREN WEBSTER AND COMPANY, A CORPORATION OF NEW JERSEY.

STEAM TRAP OR VALVE.

1,037,228.

Specification of Letters Patent.

Patented Sept. 3, 1912.

Application filed May 14, 1910. Serial No. 561,273.

To all whom it may concern:

Be it known that I, JAMES LOGAN FITTS, a citizen of the United States, and a resident of Merchantville, Pensauken township, county of Camden, State of New Jersey, have invented an Improvement in Steam Traps or Valves, of which the following is a specification.

My invention has reference to steam traps and valves and consists of certain improvements which are fully set forth in the following specification and shown in the accompanying drawing, which forms a part thereof.

15 The object of my invention is to provide an effective construction of trap or valve which shall operate thermostatically to control a thoroughfare or passage to permit the escape of water and air but prevent the escape of steam and more particularly my invention is intended for use as a return valve between the radiators and return pipes of a steam heating system, in which case the object of the device is to permit the free 25 escape of the water of condensation and air from the radiator into the return pipe while restricting or preventing the escape of steam,

My invention embodies in its construction a valve body having inlet and outlet ports 30 in communication through a thoroughfare, a valve adapted to control the thoroughfare and preferably arranged to be rotated to grind the same upon its seat when necessary, an expansible thermostatic member contained within and in communication with the chamber of the valve body between the thoroughfare and the outlet port whereby it is affected by the temperature conditions within the valve body, and mechanical devices between the movable part of the thermostatic member and the valve whereby the latter is moved under the expansion and contraction of the thermostatic member, the said parts, together with details of construction, 45 being fully described hereinafter, and more particularly defined in the claims.

Referring to the drawings: Figure 1 is a sectional elevation of a steam trap or valve embodying my invention; Fig. 2 is a sectional plan view of the same and Fig. 3 is a perspective view of the valve operating mechanism detached from the body and the thermostatic member.

2 is the valve body parts provided with 55 an inlet 3 and an outlet 4. The inlet 3 ter-

minates on its inner end in a thoroughfare 5 also constituting a valve seat for the valve 6. This valve 6 is provided with an annular baffle 6^a, the purpose of which will be described hereinafter. The valve 6 is provided with a wing guide 7 which fits into the thoroughfare and inlet for the purpose of supporting and guiding the valve centrally with respect to its seat and said valve is further provided with a valve stem 8 which is provided with an annular recess 11 near its free end, and also preferably provided with a transverse groove 28 in which a screw driver may be inserted and by which the valve may be rotated upon its seat 5 when desired for purposes of cleaning it and the seat of any obstructions which may adhere to them. The side of the valve body 2 is provided with a screw-threaded aperture 9 in line with the axis of the valve stem and this aperture 9 is normally closed and sealed by means of a screw plug 10. By removing the screw plug, access may be had to the valve stem 8 with a screw driver for the purpose of rotating it as above stated, and which operation may thus be performed without dismantling the trap as a whole.

12 is a bell crank or lever structure having one of its arms slotted as at 29 and so shaped as to receive and operate upon the annular grooved portion 11 and shoulders thereof of the valve stem 8, as may be clearly understood by reference to the drawings. A pin 30 may be employed in the slotted portion 29 immediately above the valve stem to prevent it riding up. This bell crank 12 is pivoted upon a pin 13 which is inserted through a hole 31 in the hub of the bell crank and also received in corresponding apertures in the body and in which it is locked or retained by means of a sealing screw 32. This construction will be better understood by reference to Fig. 2. The bell crank 12 has its other arm pivoted at 16 to a yoke 15, the arms of which extend over the valve stem 100, 8 and downward for making connection with the bell crank, as clearly shown in Fig. 3. The upper end of this yoke 15 is provided with a screw-threaded shank 17 which is screwed into a socket portion 18 on the lower 105 head of a thermostatic member 19, the upper head 20 of which is clamped to the bonnet 23 by means of a clamping nut 22 and the threaded stud 21 which extends through the bonnet from the head 20.

While the yoke under the action of the thermostatic member rocks the bell crank lever 12 for horizontally reciprocating the valve stem 8 of the valve 6, it is important that the valve shall not bind in such horizontal movement and to prevent this, I provide the bottom of the slot 29 in the upright arm of the bell crank with a curved form struck from the center of the pivot pin 13 so that it supports the valve stem 8 at all times during the rocking of the bell crank and thereby maintains the said valve stem in the same horizontal axial alinement with the center of the thoroughfare. This curved part of the arm 12 is indicated at 12^a in Fig. 1. The bonnet 23 is extended downward so as to inclose the thermostatic member and its lower end is provided with an outwardly directed flange 24 which is clamped between packing 25 and 27 and held in place upon the upper end of the body 2 by means of the flanged end 26. The thermostatic member may be of any suitable construction, but that shown and preferred is of the construction formed of sheet metal with annular bellows folds so as to be very expandible and containing a volatile fluid which is susceptible to heat and which under slight variations of said heat vaporizes and produces an internal pressure within the expandible member and thereby through the mechanical connections shown in Fig. 3 operate the valve 6. I do not make claim to the construction of the expandible member herein disclosed, as said member may be of any construction which is found suitable, but that illustrated is believed to be most efficient for the purpose of this invention. It will be observed that the thermostatic member is arranged upon the discharge side of the thoroughfare, so that it is affected by the contents of the valve body in connection with the discharge side or return pipe. In cases where the return pipe contains a partial vacuum, the thermostatic member is maintained in a normally clear condition because of the rarefaction of the contents of the body 2 than in cases where atmospheric pressure or a pressure greater than atmospheric might exist in said body.

The operation of the device will now be understood. Assuming that the inlet 3 is connected with the radiator or other steam vessel in which there is water and air to be removed while restricting the escape of steam, the normal position of the apparatus shown in Fig. 1 will be modified by the attempt of any steam or heated vapor to pass through the thoroughfare 5 into the body 2 in its escape through the outlet 4. The increased temperature so produced in the body 2 will act upon the thermostatic member 19 and cause it to expand with the result that the yoke 15 will be moved downward, the crank 12 oscillated and the valve

6 moved toward the seat on the thoroughfare 5, thereby closing the thoroughfare and preventing the passage of the steam. Any accumulation of water and air, or either of them in the radiator or other steam vessel connected with the inlet 3, may pass through the thoroughfare without closing the valve 6 because the temperature of these elements is not sufficient to cause the expansion of the thermostatic member, and consequently any abnormal accumulations of air and water will find their way through the thoroughfare and out by the outlet 4 as rapidly as such accumulations take place. Any attempt of steam to follow the air and water will instantly cause the thermostatic member to respond to close the valve 6 and thereby throttle off the escape of the steam. As the upper end of the thermostatic member is definitely located with respect to the valve, it is evident that the thermostatic member should be so adjusted upon the yoke 15 that the valve will properly seat and unseat with respect to the thoroughfare in accordance with the requirements, and this provision for adjustment is made in the parts 17 and 18, as before stated.

By arranging the valve 6 horizontally and the thoroughfare intermediate of the outlet 4 at a lower elevation and the thermostatic member 19 at a higher level, we secure the advantage in that the water of condensation is free to discharge downward, whereas the hot vapors in passing through the thoroughfare impinge upon the baffle 6^a and are caused to pass upward in contact with the thermostatic member, thereby insuring quick action thereof the moment such vapors find their way into the valve body. Furthermore, the arrangement of the horizontal valve in the manner shown insures the trap being fully drained of water of condensation and thereby avoiding the danger of stopping the operation of the apparatus which is employed by the freezing of accumulated water at times when steam is shut off. In my improved apparatus the return valve 6 is so positioned within the valve body that the water drains away from the valve and there is no possibility of it being rendered immovable by the freezing of water since no water remains within the body 2 of the valve in the construction herein disclosed.

By employing a thermostatic member of the character herein described there is capacity to give a movement of the valve piece of at least 3/15 of an inch, and consequently the discharge of scale, sand and oxid of iron, etc., which is commonly found in heating systems, is very easily accomplished without the possibility of stoppage of the valve therefrom. This form of valve device enables the same to be revolved while in position so that the valve may be ground to its

seat when required as a means of keeping the valve piece tight and in good condition, and also as a means of cutting away the dirt that might accumulate and which, if not removed, would to a greater or less extent interfere with the proper passage of water, induce loss of steam, and thereby cause more or less trouble. By reason of the fact that this valve permits a large opening of the thoroughfare under normal conditions and thereby enables the valve to keep itself clean, I am enabled to obviate the necessity of using the usual by-pass which has been heretofore employed in traps or valves of this general type. This is especially an advantage where the thermostatic member is on the outer or return side of the valve piece, as in my improvement.

While my invention is especially adapted as a return valve or trap for the return side of radiators in steam heating apparatus, it is also excellently adapted as a steam trap either for live or exhaust steam and may be employed with heating apparatus in which the steam pressure is as high as 50 pounds, and may equally be employed where the system is operated as low as from 5 pounds above atmospheric pressure to 5 pounds below atmospheric pressure; and it may also be used as a draining means for steam mains generally, cooking kettles, steam tables, or for any other apparatus in which water or condensation accumulates and must be removed from the piping without the passage of steam or excessive quantities of vapor.

While the trap is designed with the intention of employing the port 3 as the inlet and the port 4 as the outlet, it is evident that the device may be reversed in its connections, using the port 4 as the inlet and the port 3 as the outlet in which case the thermostatic expansible member would be on the side of the valve 6 which would be adjacent to the source of the heat; *i. e.*, the radiator side if it was connected to a radiator. It would be preferable, however, in making this reversed connection, to turn the trap so that the port 3 would be at the bottom and the port 4 would be at the side. It is more desirable that the trap should be employed in the manner first above described rather than in the reversed position mentioned in this paragraph, because not only is the device more responsive with the thermostatic member on the side of the valve that is most distant from the source of heat, but the passage of the water of condensation from the valve body would be more positively accomplished, and there would be less liability of the valve becoming inoperative by water freezing about it when the system was shut down in cold weather, and also less liability of the valve clogging from dirt.

I have shown my improvements in the form which I have found excellently adapt-

ed for commercial use, and therefore while I prefer the construction so illustrated, I do not confine myself to the details, as these may be modified without departing from the spirit of the invention.

Having now described my invention, what I claim as new and desire to secure by Letters Patent, is:—

1. In a device of the character described, the combination of the body having inlet and outlet ports and valve seat in connection with one of said ports, a valve for the valve seat supported so as to be freely rotatable and have means for rotating it, a bell-crank pivoted within the body and having one arm operatively connected with the valve between the valve piece and the means for rotating it to move it to or from the valve seat while permitting rotation, a thermostatic member arranged within the body and consisting of an expansible chamber containing a highly expansible substance, and an extension from the thermostatic member connected with the other arm of the bell crank.

2. In a device of the character described, the combination of the body having inlet and outlet ports and valve seat in connection with one of said ports and also having an opening through which to insert a tool to rotate the valve, a plug for normally closing said opening, a valve for the valve seat, having the end of its stem formed for receiving a tool for rotating it and in line with the removable plug in the body, a bell crank pivoted within the body and having one arm operatively connected with the valve to move it to or from the valve seat, a thermostatic member arranged within the body and consisting of an expansible substance, and an extension from the thermostatic member connected with the other arm of the bell crank.

3. In a device of the character described, the combination of the body having inlet and outlet ports and valve seat in connection with one of said ports, a valve for the valve seat guided in the inlet port and having horizontal stem, a bell crank pivoted within the body and having one arm operatively connected by a journal bearing with the valve stem to support the valve and to move it to or from the valve seat and also permit free rotation of the valve, a thermostatic member arranged within the body and consisting of an expansible chamber containing a highly expansible substance, and a yoke shaped extension from the thermostatic member extending over the valve stem connected with the other arm of the bell crank.

4. In a device of the character described, the combination of the body having a horizontal inlet formed with a valve seat and also having an outlet from the bottom and at a lower level than the inlet, a horizontally operating valve for the valve seat hav-

ing a baffle for directing the vapor passing through the inlet in an upward direction within the body, a thermostatic member within the body at a higher elevation than the inlet and valve adapted to receive the vapor directed upward by the baffle, and means connecting the said thermostatic member with the valve for operating it.

5. In a device of the character described, 10 the combination of a body having a port terminating in a valve seat and a second port at right angles to the first mentioned port, a bellows fold thermostatic member secured with the body substantially opposite to the last mentioned port therein, a valve movable to and from the valve seat and located between the last mentioned port and thermostatic member and having a baffle for directing the vapor and water 20 respectively toward the thermostatic member and the last mentioned port, and means connecting the thermostatic member with the valve for operating it.

6. In a device of the character described, 25 the combination of the body having a side inlet terminating in a valve seat and an outlet at the bottom at a lower elevation, a removable bonnet to close the upper part of the body, a thermostatic member secured to 30 the bonnet and extending downward toward the outlet, a horizontally movable valve for the valve seat so shaped as to di-

rect the vapors toward the thermostatic member and the water toward the outlet, and means connecting the valve with the 35 thermostatic member whereby the valve receives horizontal reciprocation from the vertical reciprocation of the thermostatic member.

7. In a device of the character described, 40 the combination of the body having a side inlet terminating in a valve seat and an outlet at the bottom at a lower elevation and also a normally sealed opening in its side in line with the inlet for inserting a tool for 45 rotating the valve upon its seat, a removable bonnet to close the upper part of the body, a thermostatic member secured to the bonnet and extending downward toward the outlet, a horizontally movable valve for the valve 50 seat having capacity for being rotated upon its axis, and means connecting the valve with the thermostatic member whereby the valve receives horizontal reciprocation from the vertical reciprocation of the thermostatic 55 member and is at all times capable of being rotated upon its axis.

In testimony of which invention, I hereunto set my hand.

JAMES LOGAN FITTS.
